Primary Examiner — Andrew T Nemeth

(74) *Attorney, Agent, or Firm* — McCoy Russell LLP

(57) **CLAIM**

The ornamental design for a litter scoop, as shown and described.

DESCRIPTION

1. Litter scoop

1.1 : Perspective

1.2 : Front

1.3 : Back

1.4 : Left

1.5 : Right

1.6 : Top

1.7 : Bottom

The intended use of the litter scoop is to remove a cat's waste from a litter box.

The dash-dash broken lines illustrate portions of the litter scoop that form no part of the claimed design.

(Continued)

The dash-dot broken lines illustrate a boundary of the litter scoop that forms no part of the claimed design.

1 Claim, 7 Drawing Sheets
